UNITED STATES PATENT OFFICE

WILLIAM C. HIERING, OF NEWARK, NEW JERSEY, ASSIGNOR TO J. E. MERGOTT CO., OF NEWARK, NEW JERSEY, A CORPORATION OF DELAWARE

BAG FRAME

Application filed October 28, 1929. Serial No. 402,894.

This invention relates to hand bags and more particularly to frames and latching devices for such bags.

It is an object of this invention to provide a hand bag frame having a latching device therefor so arranged that no parts project outwardly from the frame.

A further object is the provision of a hand bag frame which will greatly facilitate the manufacture of hand bags and materially reduce the cost thereof.

These and other advantageous objects, which will later appear, are accomplished by the simple and practical construction and arrangement of parts hereinafter described and exhibited in the accompanying drawing, forming part hereof, and in which:

Figure 1 represents a plan view of the hand bag frame and latch therefor.

Figure 2 represents a sectional view of the hand bag employing the frame.

Figure 3 represents an exploded perspective view of a latch used in connection with the frame.

Figure 4 represents a view of a section of the frame and the latch viewed from the side opposite to that shown in Figure 1.

Figure 5 shows a hand bag embodying the invention.

Referring to the drawing, the bag frame is shown to comprise two substantially U-shaped channelled members 5 and 6, hingedly connected together. The leather or fabric covering 7 of a handbag, together with a lining 8, has its free ends tightly clamped in the channels of the frame members.

Fixed to the underside of a horizontal portion of frame member 6 is a casing 9 having upstanding prongs 10 which are adapted to be passed through apertures in the bottom of the channel in member 6, and bent over to securely hold the casing 9.

As shown in Figure 3, the casing is provided with apertures 11 through which pass a shaft 13, the latter being provided with flattened portions 14—14 adapted to cooperate with flat springs 12 and 12', positioned in the casing, to hold the shaft in certain positions.

Integral flanges 15 and 15' substantially fill

the apertures 11, and beyond the flange 15' the shaft has a larger flange 26 which abuts against the frame and limits movement in one direction of the shaft.

Extending outwardly from flange 26 the shaft is considerably enlarged as shown at 17 in Figure 3, this enlarged portion being provided with oppositely disposed recesses 18 adapted to receive the spring forks 24 of a handle 23, by means of which the shafts may be rotated.

In order to protect the bag covering from wear due to the movement of handle 23, a washer 19 is preferably disposed between the covering 7 and the handle 23.

The shaft 13 extends beyond flange 15 to a point beneath the horizontal portion of frame member 5, where a semicircular flange 16 on the shaft 13 is adapted to enter the recessed portion 22 of the lug 20, the latter being secured to the frame member 5 by means of prongs 21.

From the foregoing description it will be seen that the latching device may be readily and conveniently attached to the underside of the horizontal portion of a frame member, thus presenting no obstructions to prevent the proper clamping of the bag covering material in the channels of the frame members.

At the same time, the arrangement of the frame members and the latch therefor enable the production of a bag in which there are no parts projecting outwardly and above the frame member. It is obvious that a bag embodying the construction herein set forth has a neat and finished appearance, and may be economically manufactured.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. A handbag frame comprising U-shaped members hinged together, each member being

channelled inwardly to provide spaced inner and outer walls extending upwardly, and outwardly, whereby the upper and outer ends of the handbag fabric can be passed over the outer surfaces of the outer walls of the channels and over the top edges of such walls and secured in position in such channels, and latching means comprising a stud having a recess mounted on the bottom wall of one member, and a shaft rotatably mounted on the bottom wall of the other member, said shaft having a semi-circular flange arranged to enter the recess in the stud, said shaft extending through and operable from the outside of the hand bag fabric.

2. In a handbag frame comprising U-shaped members hinged together, each member being channelled inwardly to provide spaced inner and outer walls extending upwardly and outwardly, whereby the upper and outer ends of the handbag fabric can be passed over the outer surfaces of the outer walls of the channels and over the top edges of such walls and secured in position in such channels, a latching means comprising a stud having a recess mounted on the bottom wall of one member, a shaft rotatably mounted on the bottom wall of the other member, said shaft having a semi-circular flange arranged to enter the recess in the stud, and resilient means to retain the shaft in either an unlatched or latched position, said shaft extending through and operable from the outside of the hand bag fabric.

3. In a handbag frame comprising U-shaped members hinged together, each member being channelled inwardly to provide spaced inner and outer walls extending upwardly and outwardly, whereby the upper and outer ends of the handbag fabric can be passed over the outer surfaces of the outer walls of the channels and over the top edges of such walls and secured in position in such channels, a latching means comprising a stud having a recess depending from the underside of one member, a shaft rotatably mounted on the underside of the other member, means on the shaft to enter the recess to hold the members in a latched condition, and means to retain the shaft in either a latched or an unlatched position, said shaft extending through and operable from the outside of the hand bag fabric.

4. In a handbag having a frame comprising U-shaped members hinged together, each member being channelled inwardly to provide spaced inner and outer walls extending upwardly and outwardly whereby the upper and outer ends of the handbag fabric can be passed over the outer surfaces of the outer walls of the channels and over the top edges of such walls and secured in position in such channels, a latching element depending from the underside of one frame member, and a rotatable latching element cooperating with

the first mentioned latching element, said rotatable latching element depending from the underside of the other frame member, said rotatable latching element extending through and operable from the outside of the hand bag

This specification signed this 25th day of October, 1929.

WILLIAM C. HIERING.
